COMBINATION BOTTLE OPENER AND CAN OPENER

Clarence W. Brewer, Decatur, Ill.

Application July 13, 1950, Serial No. 173,592

3 Claims. (Cl. 30—6.1)

1

My present invention relates to a combined bottle opener and can opener adapted to be mounted upon a vertical surface with respect to the floor or the like.

It is an object of my invention to provide a wall mounted holder for can opener blades and a bottle opener for household use, whereby the respective openers are always in ready position for use.

Another object is to provide a fore and aft aligned arrangement of can opener blades adapted to form a first relatively large liquid pouring opening in a can and then a smaller air intake opening in the can.

Another object is to provide an attractive unit of durable and economic construction, which can be readily manufactured in mass production.

Other objects will appear from the following description, reference being had to the accompanying drawings.

Fig. 1 is a side elevation of my present invention.

Fig. 2 is a top plan view of the same.

Fig. 3 is a bottom plan view of the same.

Fig. 4 is a front elevation of the same.

Fig. 5 is a rear elevation of the same.

Fig. 6 is a sectional view taken on the line 6—6 of Fig. 2 and showing the device as adapted to use blade members shown in Figs. 7 and 8.

Fig. 7 is a front elevational view of the first blade member for removing a bottle cap and also for gripping the peripheral bead on the end of the can, taken in the position shown in Fig. 6.

Fig. 8 is a front elevational view of the second blade member for forming both the liquid pouring opening and the air intake opening, taken in the position shown in Fig. 6.

Fig. 9 is an end view of a beer can after being pierced and shows the type of openings made by the device.

Fig. 10 is a front elevation showing the retainer portion which holds the blade members in position.

Fig. 11 is a rear elevation of the retainer portion shown in Fig. 10.

Fig. 12 is a sectional view taken on the line 12—12 of Fig. 10.

Fig. 13 is a sectional view similar to Fig. 6 but showing a different type of blade members.

Fig. 14 is a front elevational view of one blade member shown in Fig. 13.

Fig. 15 is a side elevational view in outline only, to show the first position of the beer can thus held to begin the piercing operation of the liquid pouring hole.

2

Fig. 16 is a view similar to Fig. 15 but showing the can in the second position as when the liquid pouring hole is pierced.

Fig. 17 is a view similar to Figs. 15 and 16 and showing the can in the third position as when the air intake hole is pierced, after which the can is simply lowered for removal and use.

Referring to the drawings and first with particular reference to Figures 1, 2, 4, and 6, there

10 is illustrated a bracket 10 formed with a triangular base surface 11 and an elongated hood-shaped body 12. Each corner of the base 11 is formed with notches 13 for receiving suitable fastening members, not shown, when the same is to be mounted on a wall or like vertical surface. An elongated longitudinal reinforcing rib 14 may be formed from the top of the hood body, which rib may extend to the concavo-convex free end of the body.

20 The underside of the body 12 is formed medially with longitudinally spaced fore and aft rearwardly slanting supporting surfaces 15 and 16 respectively. Can cutting or punching members 17 and 18 are clamped onto these supporting surfaces by a compound clamp member 19, see Figs. 10, 11 and 12. This clamp member 19 includes similar rearwardly slanting fore and aft surfaces 20 and 21 to the longitudinally spaced fore and aft supporting surfaces 15 and 16 of the body 12. Each of the fore and aft surfaces 15—16 are provided with threaded holes for the screws 22 and 23, respectively, while the fore and aft surfaces 20 and 21 are provided with smooth through holes to slip said screws 22 and 23, see Fig. 6. The slanting fore and aft surfaces 20 and 21 are spaced apart by a slot 24. At the rear of the slot 24 is a depending curved lip 25 which serves as a backing or brace for the liquid pouring hole punch or cutter portion 26 of the blade member 18.

30 40 The cutter portion 26 as shown in Fig. 6 is formed integrally with the cutter portion 27 which punches the air intake hole, each of which cutters form the legs of an inverted U-shaped structure 18 held clamped upon the aft supporting surface 16 by clamping surface 21 and screw 23 threaded into the aligned threaded and smooth holes of the said respective surfaces.

Clamped by the surface 20 and screw 22 upon the fore or first supporting surface 15 is a compound implement 17 of flat metal blade 28. This implement comprises a hooked end 29 housed in the concave free end of the body 12 serving as a bottle opener and a tip 30 slightly curved to conform to the peripheral bead 32 of a can to be

opened, see Fig. 14. This tip 30 thus serves as a fulcrum point for the can as it is radially moved into progressive contact with the fore and aft can opening members 26 and 27. The can is guided into initial position by an arcuate yoke 31 formed from the clamp member 19. As shown in Fig. 9 the lower part of the end of a can will be punctured first by cutter or punch 26 to form a hole 26^a for liquid pouring and second by cutter or punch 27 to form a somewhat smaller air intake hole 27^a.

The compound structure of the blade member 28 with the hooked end 29 of the implement 17 cooperates with the head of bolt 22 to open a bottle 33. The bottle 33 is illustrated with the usual crimped cap 34 in Fig. 13 by dotted lines. Although this figure shows the opener punch blade 26 formed integrally with the blade 28 instead of separate therefrom as shown in Fig. 6, the bottle opening maneuvers are the same. For example, the edge of the hooked blade end 29 grips under the edge of the bottle cap 34 and as the bottle is angularly moved the top of the cap presses against the top of the head of screw 22. This provides a lever action adapted to quickly remove the bottle cap, and the bolt head dents the cap inwardly, thereby to loosen the cap by letting in air around the edge as the lever action progresses.

As just stated in the above paragraph the modification illustrated in Fig. 13 includes all the same elements of the first modification in Fig. 6, except that blade 26 is cut off of the inverted U-shaped structure of the member 18 and combined with the blade member 17. Accordingly, the same numerals are applicable to both forms.

Without further description, the operation and use of the novel device is believed to be understandable so as to permit others to readily practice the invention. For example, Figs. 15, 16 and 17 clearly illustrate the progressive action of the fore and aft cutting blades 26 and 27 of the member 18 upon a can being opened. The arcuate yoke 31 serves to initially center the can with respect to the blades.

Then in Fig. 13 the application of the bottle opener arrangement is clearly illustrated.

While I have illustrated and described two particular embodiments of my invention, it will be apparent to those skilled in the art that the principles thereof may be utilized in other embodiments. I, therefore, do not intend the present invention to be limited to the particular embodiments disclosed. Reference should be had to the appended claims to determine the scope of my present invention.

What I claim is:

1. A can opener substantially as herein described, comprising a bracket having a base for attachment to a wall or the like, said bracket having a body formed with the base, the under part of said body being proportioned and shaped at intervals longitudinally from the free end thereof with fore and aft rearwardly slanting

supporting surfaces and can punching means clamped to each of said surfaces, one of said punching means including a hooked end engageable under the outer bead at the top of a can to be opened to serve as a fulcrum point from which the can may be radially moved into progressive engagement with each of the can punching means.

2. A can opener substantially as herein described, comprising a bracket having a base for attachment to a wall or the like, said bracket having a body formed with the base, under part of said body being proportioned and shaped at intervals longitudinally from the free end thereof with fore and aft rearwardly slanting supporting surfaces, can punching means clamped to each of said surfaces, one of said punching means including a hooked end engageable under the peripheral bead at the end of a can to be opened to serve as a fulcrum point from which the can may be radially moved into progressive engagement with each of the can punching means, a compound clamp member having similar rearwardly slanting fore and aft surfaces to said aligned supporting surfaces, the under part of said free end of the body being formed with a first concave recess ahead of the leading supporting surface of the body, and a second recess ahead of the following supporting surface, said slanting surfaces of the clamp member and said supporting surfaces of the body being formed with smooth and threaded holes respectively, and screws for securing the two fore and two aft slanting surfaces together for clamping and punching means in their respective fore and aft positions to the underside of the body.

3. A can opener comprising a bracket having a base for attachment to a wall or the like, said bracket having a body formed with the base, the under part of said body being proportioned and shaped at intervals longitudinally from the free end thereof with fore and aft rearwardly slanting supporting surfaces and can punching means clamped to each of said surfaces, one of said punching means including a hooked end engageable under the peripheral bead at the end of a can to be opened to serve as a fulcrum point from which the can may be radially moved into progressive engagement with each of the can punching means, and an arcuate yoke adapted to center a can to be opened with respect to the can punching means.
